INVENTOR

Victor J. Evans

ATTORNEY

UNITED STATES PATENT OFFICE.

WILLIAM M. MYERS, OF HANNIBAL, MISSOURI.

BELT BUCKLE.

Application filed March 13, 1922. Serial No. 543,312.

To all whom it may concern:

Be it known that I, WILLIAM M. MYERS, a citizen of the United States, residing at Hannibal, in the county of Marion and 5 State of Missouri, have invented new and useful Improvements in Belt Buckles, of which the following is a specification.

This invention relates to buckles and has for its object the provision of a novel buckle 10 for use upon belts, straps, and the like, whereby the ends of the straps may be secured in a very efficient manner so as to positively prevent any slipping, the construction of the buckle being such that it 15 is provided with retaining means of peculiar formation engaging the belt or strap for holding the parts associated, the buckle being furthermore provided at its other end with a tongue which is bent back to 20 constitute a keeper engaging the end of the strap, the buckle being furthermore provided with a locking bar operating along inclined slots.

An additional object is the provision of 25 a buckle of this character which will be simple and inexpensive in manufacture, easy to install and use, highly efficient in service, and a general improvement in the art.

With the above and other objects and 30 advantages in view, the invention consists in the details of construction to be hereinafter more fully described and claimed and illustrated in the accompanying drawings in which—

35 Figure 1 is a front elevation of the buckle in position upon a strap.

Figure 2 is a rear elevation.

Figure 3 is a longitudinal section.

Figure 4 is a detail perspective view.

40 Referring more particularly to the drawings, I have shown my buckle as comprising a body 10 which is preferably longitudinally curved, as shown, and which is formed with spaced parallel flanges 11 at its edges, 45 these flanges being formed of inclined slots 12 through which is slidably engaged a lock bar 13. This locking device is itself old and well known and I claim no novelty for it, though it is illustrated as forming

50 part of my completed buckle. The essential feature of the invention is the formation, at the ends of the body, of tongues 14 and 15, the former of which is bent back upon itself, as indicated at 16, into 55 clamping engagement with the end of the strap or belt A which is disposed against

the rear side of the body. The tongue 15 is bent back, as shown at 17, and is then rebent, as shown at 18, so as to extend substantially parallel with the body 10 but 60 offset rearwardly with respect thereto. This tongue 15 thus constitutes a hook and adjacent its junction with the body, it is cut away at opposite sides to define a constricted neck 19 upon which is of course formed the 65 head 20 which is somewhat larger than the neck and which tapers to a substantial point 21. The belt or strap is formed with a hole 22 which is engaged upon this hook-like tongue whereby the buckle is held associated 70 with the strap or belt.

In the use of the device, after the belt or strap is placed about the waist, in case it is designed for this purpose, or after it is placed about anything else which it is desired to hold, the free end of the belt is inserted between the rear side of that end which is secured to the buckle and passes between this second mentioned end and the lock bar 13. The free end of the belt is 80 then pushed along until the proper tightness is had, whereupon any tendency toward slipping will be prevented owing to the fact that the lock bar will be urged into the ends of the slots nearest the plate portion of the 85 buckle, this of course resulting in a firm clamping action so that the greater the pull tending to loosen the belt the greater will be the clamping action of the lock bar. Owing to the fact that when the belt is applied, 90 both ends are in engagement, it will be seen that there will be a greater degree of friction tending to hold the parts together than in the ordinary construction.

While I have shown and described the 95 preferred embodiment of my invention, it is of course to be understood that I reserve the right to make such changes in the form, construction and arrangement of parts as will not depart from the spirit of the invention 100 or the scope of the subjoined claims.

What is claimed is:—

1. A belt buckle comprising a body of plate-like form provided at its edges with flanges formed with inclined slots, a lock-bar 105 slidably along said slots, tongues formed on the ends of the body and bent backwardly with respect thereto and lying substantially parallel therewith, and a strap disposed against the rear side of the body with one 110 end abuttingly engaging one tongue and formed at a point spaced from said end with

a hole within which the other tongue is received.

2. A belt buckle comprising a plate-like body formed at its side edges with spaced parallel flanges provided with inclined slots, a lock bar slideable along said slots and tongues formed at the ends of the body, one tongue being bent back upon itself into spaced parallel relation to the front of the body to define an abutment for the free end of the strap, and the other tongue being offset rearwardly with respect to the body and having a constricted neck portion and a relatively large head terminating in a substantial point, the strap being formed with a hole through which said second named tongue is disposed.

3. A belt buckle comprising a plate like body formed at its side edges with spaced parallel flanges provided with inclined slots, a lock bar slideable along said slots, and tongues formed at the ends of the body, one tongue being bent back upon itself into spaced parallel relation to the front of the body to define an abutment for the free end of the strap and the other tongue being offset rearwardly with respect to the body and extending in the same direction as the first named tongue, the strap being formed with a hole through which said second named tongue is disposed.

In testimony whereof I affix my signature.

WILLIAM M. MYERS.
